UNITED STATES PATENT OFFICE

PASQUALE PASCALE, OF NEW YORK, N. Y., ASSIGNOR TO DRI-STEAM VALVE CORPORATION, A CORPORATION OF DELAWARE

LOCOMOTIVE VALVE

Application filed December 20, 1929. Serial No. 415,475.

This invention relates to a locomotive valve.

In my Patent Number 1,647,465, of November 1, 1927, there is involved a valve, 5 using the same principles as the present one and the valve referred to is very efficient in operation, serving, in accordance with the objects and purposes therein stated, to efficiently dry the steam before it passes to the 10 place where its power is utilized.

In the patent referred to there is shown and described a balanced stop valve combined with means for drying the steam, the drying means including elements termed a 15 "turbine", consisting of an annular cage entirely surrounding the valve body, and made up of numerous vanes, through which the steam must pass, the vanes being so spaced as to form numerous narrow passages between them, the passages being of such width 20 that the steam will be denuded initially of much of its moisture before reaching the point where it passes through the second element, which is termed the "steam drier", and 25 which consists of a hollow cylinder provided, throughout the greater part of its surface, with small perforations or nozzles through which the steam finally passes in entering the valve body, the perforations acting to further 30 denude the steam of moisture and to deliver it in substantially dry condition to the place of utilization, or to superheaters or the like, that may intervene between the valve and the point of use.

The object of this invention is to improve 35 on my former valve by the provision of a construction that even more efficiently dries the steam and to this end, the invention consists in the main, and in a broad sense, in interrupting the flow of steam from the turbine 40 to the "steam drier" or perforated cylinder or sleeve, by the interposition of a barrier or diaphragm between these elements that prevents the incoming steam from being brought 45 directly into contact with the drier, the barrier or diaphragm, together with the outer wall of the casing and the valve body, forming multiple conduits communicating with each other, there being also provided, means 50 whereby the water extracted from the steam

is quickly and conveniently led back into the boiler. There is provided in the present construction, as in the construction shown and described in my Patent Number 1,710,- 55 946, April 30, 1929, means for balancing the valve.

A further object of the invention is to so locate the steam drier with relation to the valve body that the steam will pass through the drier before entering the ports in said body, thus facilitating the quick return to the boiler of the moisture in highly heated condition.

In the drawings illustrating the invention, 60 Figure 1 is an elevation of the valve with so much thereof in section as is necessary to show the internal construction.

Figure 2 is a section taken about on line 65 *a—a* of Figure 1.

Figure 3 is an elevation partly in section 70 of the lower portion of the valve structure, and

Figure 4 is a fragmentary section showing 75 the arrangement of the vanes or the turbine ring.

Referring to the drawings, the numeral 1 designates the outlet pipe casting designed for connection with a superheater or other means for conducting the steam to the point where it is utilized. This casting is provided in the present instance with a drainage chamber 2, which may be in turn provided with a fitting or fittings 3 through which the water extracted from the steam is 80 returned to the boiler.

The numeral 4 designates the valve body formed at its lower end with an annular flange 5 having a similarly shaped opening 6 therein, extending entirely around the body, the purpose of which will presently become apparent. The body 4 is surrounded by an annulus 7 having formed at its upper outer edge, the beveled valve seat 8. The body is provided with a number of ports 9, through which steam passes into the body. The body is provided at its upper end with a head 10 having a dome-shaped central portion 11 to receive the pilot or relief valve which will be presently described.

The numeral 12 designates what I term 100

the steam drier. This is constituted by a sleeve or cylinder having an inturned flange 13 at its upper end adapted to rest upon an annular ledge or rabbet 14 in the head of the 5 valve body and securely held therein by a ring 14' secured to the head by bolts 15, the ring 14' being provided with upwardly and downwardly extending flanges 16 provided at intervals with annular grooves 17 for the reception 10 of suitable packing rings 18, the part just described being the equivalent of the means shown and described in my Patent Number 1,710,946, of April 30, 1921, wherein said means cooperates, by reason of certain 15 proportional dimensions, of the valve seat and valve, to aid in balancing the valve.

The numeral 19 designates the valve to which is secured by bolts 20, the head 21, provided with a central boss 22 for the reception 20 of the pilot valve 23. The valve 19 envelops, when closed, the greater portion of the valve body, and obviously is slidable thereon, and its lower edge is shaped to conform to the valve seat 8 on the annulus 9. 25 Surrounding the valve and valve body is an outer casing 24, and an inner diaphragm or casing 25, spaced apart as shown, so as to provide two annular chambers, an outer chamber 26 and an inner chamber 27, which 30 form conduits through which the steam enters before reaching the interior of the valve. Surrounding the valve and forming a part of the outer conduit and communicating with the chamber 26, is a turbine or cage 28, which 35 is formed as a part of the upper casing section 29, which is suitably secured to the lower casing section 30, and to a flanged ring 31 at the top of the structure. This turbine is constituted by a ring 32 having formed in- 40 tegral therewith, numerous vanes 33, so spaced as to form numerous narrow passages through which steam must pass before passing into the chamber 26, the bottom of the turbine or ring 32 being provided with an opening 45 communicating with the said chamber 26. Preferably the passages between the vanes of the turbine are arranged tangential to the axis of the valve and the turbine, as a whole, is preferably made up of a number of sections 50 with the angles of the vanes in different directions, the sections being in alternate arrangement.

The lower ends of the chamber 26 and 27 55 are open and in communication, and they are also in communication with the drainage opening 6 of the valve body.

Braces 34 are provided at intervals around the structure for the purpose of firmly securing the walls 24 and 25 together, and similar braces 34' are provided between the upper 60 end of the wall 25 and the upper part of the casing for further stabilizing and bracing these parts. These braces, it will be understood, are arranged at intervals and do not

close communication between the turbine and the inner chamber 27.

The cylinder or steam drier 12 is provided with numerous small openings 36 constituting nozzles and aside from the location of this "drier" relative to the ports in the valve body, its construction does not differ materially from similar elements appearing in my patents herein mentioned.

The pilot or relief valve 23 comprises a 75 stem 37 into which is threaded a shank 38 provided with a head 39 at its lower end. Secured to the upper end of the stem by a pin 40, are cross bars 41, having suitable connection with the usual operating levers partially shown in dotted lines, whereby the valve is lifted in the initial movement of the operation of the valve to permit steam to flow in through the valve to fill the space between the head of the valve body and the 85 valve head 21. It will be noted that the valve stem is provided, just below its seat 42, with an annular recess 43, which recess communicates with the space between said heads by means of grooves 44, so that when the stem is 90 lifted, and the valve leaves its seat, steam will flow in the annular recess and through the grooves to its destination, the extent to which the valve may be opened, depending upon the amount of movement the stem can have according to the adjustment of the head 39 with relation to the bottom of the boss 22.

In operation, assuming that there is an opening movement of the valve, steam passes 100 through the vanes of the turbine in the first conduit or chamber 26, and its forceful impingement with the surfaces of the vanes and against the diaphragm 25, will denude the steam of much of its moisture or water, which, gathering outside of the wall, will 105 pass out of the bottom of this conduit in the drainage chamber, and the steam, in its thus improved condition, passes into the valve body through the perforations or nozzles 36 in the steam drier 12, reaching the interior 110 of the body in substantially dry condition. The moisture wrung from the steam by passing through the drier, condenses on the face of the drier, and flows back into the drainage chamber, through the openings 6. 115

From the foregoing, it will be seen that by the interposition of the diaphragm or barrier 25, between the outer wall of the casing and the valve body, the steam is prevented from coming directly into contact with the steam drier, as was the case in my patents above referred to.

What I claim is:

1. In a locomotive valve, in combination, 125 a hollow ported body closed at its top and provided with an annular valve seat, a valve slidable longitudinally of the body to cover and uncover said ports, and adapted to seat on said seat, a multiple casing surrounding the body and forming inner and outer con- 130

duits communicating with the ports in the body when the valve is open, means at the entrance of the outer conduit for denuding the steam of moisture and means located at 5 the entrance of the ports to further dry the steam.

2. In a locomotive valve, in combination, a hollow ported body, closed at its top and provided with an annular valve seat, a valve

10 slideable longitudinally of the body to cover and uncover said ports, and adapted to seat on said seat, a multiple casing surrounding the body and forming inner and outer conduits communicating with said ports in the

15 body when the valve is open, means located at the entrance of the ports for drying the steam.

3. In a locomotive valve, in combination, a hollow ported body closed at its top, and

20 provided with an annular valve seat, and a valve slideable longitudinally of the body to cover and uncover said ports, and adapted to seat on the seat, means located at the entrance of the ports in said body, comprising

25 a cylinder provided with numerous small holes therein constituting nozzles, a casing surrounding the valve and valve body and having steam inlet openings therein, and a diaphragm or barrier interposes between the

30 outer wall of the casing and said valve body, and forming with said valve body, a conduit open at its upper end for the downward passage of the steam to the ports in the valve body.

35 4. In a locomotive valve, in combination, a hollow ported body closed at its top and provided with an annular valve seat, a valve slideable longitudinally of the body to cover and uncover said ports and adapted to seat

40 on said seat, a multiple wall casing surrounding said body, there being a steam inlet opening in the outer casing, the inner wall forming, together with the outer wall and valve body, a plurality of steam conduits, said

45 conduits communicating with each other, the inner wall of the casing serving as a barrier to prevent the steam from passing directly into the valve body for the purpose set forth, means located opposite the ports in the valve

50 body, to dry the steam, and means for draining back into the boiler, the moisture extracted from the steam.

55 5. In a locomotive valve, in combination, a hollow ported body closed at its top and provided with an annular valve seat, a valve slideable longitudinally of the body to cover and uncover said ports and adapted to seat on said seat, a multiple casing surrounding the body and forming inner and outer con-

60 ducts communicating with the ports in the body, when the valve is open, a turbine, surrounding the outer part of the casing and constituted by numerous vanes spaced apart to form narrow steam passages, said cage

65 communicating with said conduits, a cylin-

der or sleeve provided with numerous small perforations constituting nozzles and located at the entrance of the ports in the valve body and means for draining the water extracted from the steam in passing through the turbine and means for draining the moisture from the steam after it has passed the turbine and before it passes through said perforations in the sleeves.

70 6. In a locomotive valve in combination, a hollow ported body closed at its top and provided with an annular valve seat, a valve slideable longitudinally of the body to cover and uncover said ports, and adapted to seat on said seat, a multiple wall casing surrounding the body and forming communicating conduits, said conduits being open at their lower ends to permit drainage of moisture extracted from the steam, a drainage chamber below the casing and communicating with the conduits, means for admitting and drying steam as it enters the first conduit, and means for further drying the steam as it passes into the valve body.

75 In testimony whereof I affix my signature. 90
PASQUALE PASCALE.
